US00D763295S

(12) **United States Design Patent**
Zuckerberg et al.

(10) **Patent No.:** **US D763,295 S**
(45) **Date of Patent:** **** Aug. 9, 2016**

(54) **DISPLAY PANEL OF A PROGRAMMED COMPUTER SYSTEM WITH A GRAPHICAL USER INTERFACE**

(71) Applicant: **Facebook, Inc.**, Menlo Park, CA (US)

(72) Inventors: **Mark E. Zuckerberg**, Palo Alto, CA (US); **Eyal Michael Sharon**, San Francisco, CA (US)

(73) Assignee: **Facebook, Inc.**, Menlo Park, CA (US)

(**) Term: **15 Years**

(21) Appl. No.: **29/532,474**

(22) Filed: **Jul. 7, 2015**

CLAIM

We claim the ornamental design for a display panel of a programmed computer system with a graphical user interface, as shown and described.

DESCRIPTION

The FIGURE is a front view of a display panel of a programmed computer system with a graphical user interface. The broken lines of the display panel are included for the purpose of illustrating environmental structure; the broken lines form no part of the claimed design.
